United States Patent

Des. 235,986
Patented July 22, 1975

235,986

BOAT DOCK BUMPER

George I. Nielsen, 469 Minnesota Ave.,
Roseville, Minn. 55113

Filed May 28, 1974, Ser. No. 473,433

Term of patent 14 years

Int. Cl. D12—16

U.S. Cl. D12—168

FIG. 1 is a top plan view of a boat dock bumper showing the new design.

FIG. 2 is a side elevational view thereof.

FIG. 3 is a bottom plan view thereof.

FIG. 4 is an end elevational view thereof.

I claim:

The ornamental design for a boat dock bumper, as shown.
